(57) **CLAIM**

I claim the ornamental design for guitar slide, as shown and described.

DESCRIPTION

FIG. 1 is a top perspective view of a guitar slide showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The evenly spaced broken lines represent the portions of the guitar slide that form no part of the claimed design. The dot-dashed broken lines indicate the boundary of the claim and form no part of the design.
